UNITED STATES PATENT OFFICE.

EVERETT T. ROGERS AND FRANK M. ROGERS, OF BAY SHORE, NEW YORK.

FLOOR SCRUBBING AND MOPPING MACHINE.

1,310,296.

Specification of Letters Patent. Patented July 15, 1919.

Application filed August 23, 1916, Serial No. 116,446. Renewed December 17, 1918. Serial No. 267,211.

To all whom it may concern:

Be it known that we, EVERETT T. ROGERS and FRANK M. ROGERS, citizens of the United States, and residents of Bay Shore, 5 in the county of Suffolk and State of New York, have invented a new and Improved Floor Scrubbing and Mopping Machine, of which the following is a full, clear, and exact description.

10 This invention relates to floor cleaning machines of that type including a rotary scrubbing brush and a mop operative behind the brush to take up the soapy water and dirt from the floor as the machine is run over the latter.

The present invention has for its general objects to improve and simplify the construction of machines of this character so as to be reliable and efficient in use, comparatively simple and inexpensive to manufacture and so designed as to insure a better cleaning of the floor surface by reason of the novel arrangements of the instrumentalities which are embodied in the machine.

20 25 A more specific object of the invention is the provision of a novelly supported endless mop which takes up the soapy water and dirt from the surface acted on by the scrubbing brush, and before being subjected to the action of the wringer the dirt-bearing portion is sprayed with soapy water and then acted on by a high speed revolving brush to remove the dirt, sand and the like and discharge such matter into a suitably arranged tank.

30 35 A further object of the invention is the provision of simple, effective and novel means for compensating for the shrinking and stretching of the endless mop and for maintaining the same with a portion in its most effective relation to the floor surface for mopping up the dirt and water.

40 45 A further object is to provide a novel wringer which is removably mounted in the frame of the machine and composed of hingedly connected sections whereby the wringer can be opened to receive or release the mop.

50 55 An additional object is the employment of a sprinkling device for sprinkling soapy water from the reservoir or tank to the floor just in advance of the rotary scrubbing brush and also to the dirty portion of the mop, to insure a better cleaning thereof, the sprinkling device being controlled by a

suitable means operable from the handle of the machine.

A further object of the invention is to provide a machine which can be easily pushed over the floor and is operative only 60 during the forward motion, the design and arrangement of the parts being such that the machine can work close to the walls, and furthermore, no wheel tracks are left.

With such objects in view, and others 65 which will appear as the description proceeds, the invention comprises various novel features of construction and arrangement of parts which will be set forth with particularity in the following description and 70 claims appended hereto.

In the accompanying drawings, which illustrate one embodiment of the invention and wherein similar characters of reference indicate corresponding parts in all the 75 views,

Figure 1 is a side view of the machine;

Fig. 2 is a vertical section thereof;

Fig. 3 is a plan view of the machine;

Fig. 4 is a side view of the wringer, portion in section, on the line 4—4, Fig. 2;

Fig. 5 is a horizontal section on the line 5—5, Fig. 1; and

Fig. 6 is a detail sectional view on the line 6—6, Fig. 1.

Referring to the drawing, A designates a frame of any approved construction which is provided with handles 1 for convenience in moving the machine from place to place or over the surface to be washed. In the 90 present instance the operating parts of the machine derive power from large traction wheels 2 which bear on the floor surface, but, if desired, the power may be derived from an electric motor suitably arranged on the 95 frame. The wheels 2, which are at the rear of the machine, are mounted on an axle 3 journaled in bearings 4, and on the axle are ratchet wheels 5 with each of which co-operates a pawl 6 on the adjacent traction 100 wheel 2, whereby rotation of the wheels in a clockwise direction, Figs. 1 and 2, will drive the shaft or axle 3, that in turn transmits power to the various operating devices of the machine; and rotation of the traction 105 wheels in the opposite direction, as when the machine is moved backwardly, does not impart power to the operating devices as the pawls 6 idly ride over the teeth of the ratchet wheels 5. At the front of the 110

machine are fore-wheels 7 mounted on an axle 8 which is journaled in bearings 9. These bearings are vertically adjustable in guides 10 by means of set-screws 11 which by being turned can bring the scrubbing brush into proper relation with the floor surface.

The scrubbing brush B, which is of the rotary type, is mounted with its axis horizontal, and the journals 11 on the ends thereof are disposed in bearings in the bottom side bars 12 of the frame. Fastened to one end of the brush is a pulley 13 around which passes a driving belt 14, the same extending upwardly at one side of the machine and running around an intermediate pulley 15. This pulley is in turn driven by a belt 16 which passes around a pulley 17 that is connected with a large sprocket wheel 18. Engaged with this sprocket wheel is a chain 19 that receives power from a small sprocket wheel 20 that is in turn connected with the main shaft or axle 3 by gear wheels 21 and 22.

At the front part of the machine is a tank C which contains water, as shown in Fig. 2, and suspended in the water is a basket or holder 23 for soap, whereby the water is rendered soapy. This cleaning water is sprinkled on the floor by means of a horizontal sprinkler 24, connected with the bottom of the tank by a pipe 25, said sprinkler being positioned directly in front of the scrubbing brush B. The feed of the water as well as the turning on or cutting off thereof from the tank is controllable from the handle 1 by any suitable means, such as a valve 26 in the pipe 25, which valve has an arm 27 connected by a rod 28 with an operating lever 29 fulcrumed on the handle and held locked in any desired position by a toothed bar or quadrant 30.

Behind the scrubbing brush B is an endless mop D which passes under spaced pressure rolls 31 and 32 having journals 33 engageable in inclined slots 34 in the bottom bars 12 of the frame, there being a plurality of bearing slots 34 for the roll 32, whereby this roll can be adjusted to different positions as the mop contracts or stretches. These rolls 31 and 32 are parallel and they maintain the lower part or stretch of the endless mop in proper relation with the floor surface and press the mop against the same. The mop also passes around rolls 35 and 36 mounted respectively behind the scrubbing brush B and adjacent the top of the machine, and at a point above the roll 36 the mop passes around the lower roll 37 of the wringer E, thence downwardly to the pressure roll 32. The mop is driven by the coating rolls 37 and 38 of the wringer, which also serves to remove the dirty water from the mop and thereby present a comparatively dry portion to the floor so as to

mop up the water and dirt. The rolls 37 and 38 of the wringer are connected together by gears 39, and the lower roll 37 has one journal extended to carry the sprocket wheel 18 and the pulley 17. In this manner the 70 rolls of the wringer are driven from the traction wheels 2 by means of the gears 21 and 22, sprocket wheel 20, sprocket chain 19 and sprocket wheel 18. The rolls 35 and 36 are removably mounted, as are also the rolls 75 31 and 32, whereby the endless mop can be removed from the machine. As shown in Fig. 6, the roll 35 or 36 has one journal 40 entered in an opening 41 in one side of the frame and the other journal 42 rests in a 80 bearing 43 at the opposite side of the frame and is removably held in such bearing 43 by a cap plate 44. By removing the cap plate the roller can be lifted out of the bearing 43 and then pulled longitudinally to disengage 85 the journal 40 from the journal bearing 41.

The wringer E is made with its frame in two sections e and e', and these sections are hingedly connected at one end of the frame by the hinge 45, whereby the upper section 90 e can be swung upwardly and to one side of its normal position so as to permit the mop to be inserted between or removed from the rolls 37 and 38 of the wringer. Obviously before the wringer can be opened or taken 95 out of the machine the teeth 16 and the sprocket chain 19 are first removed from the pulley 17 and sprocket wheel 18, respectively. The wringer is bodily removable from the machine, and for this purpose the 100 sides of the frame are provided with vertical guideways or recesses 46, as shown in Figs. 3 and 5, into which the wringer frame is engaged. Under the wringer frame are set-screws 47 mounted on the frame of the 105 machine, and by means of these set-screws the wringer can be raised or lowered to thereby adjust the tension of the endless mop.

In the frame of the machine is a waste 110 tank F located within the endless mop and directly under the wringer so as to catch the water wrung from the mop by the wringer it being understood that the mop travels in an anti-clockwise direction, Figs. 1 and 2. 115 This tank F is removably supported on a removable shelf 48 supported in the frame of the machine, the tank and shelf being removable for the same purpose as the rolls 31, 32, 35 and 36, that is to say, to permit 120 the mop to be taken out. After the tank and shelf and rollers are removed, the wringer can be lifted out with the mop hanging thereon, and then the wringer can be opened to permit the mop to be detached. 125

As the wringer is incapable of removing dirt from the mop, a revolving cleaning brush operates on the mop at a point between the wringer and where the mop takes up the dirty water from the floor. This brush G, 130

is mounted in the frame A at a point adjacent the roll 36 and is driven by the pulley 15, which is attached to one of the journals. This brush operates against the mop and 5 throws off the dirt into a dirt-collecting box g mounted in front of and below the brush. To assist in the cleaning action a sprinkler 50 sprinkles soapy water on the ascending stretch of the mop and at a point below the brush G. This sprinkler is connected with 10 the pipe 25 by a branch 51 which has a valve 52 for regulating the flow of water.

The mop is wider than the gage of the machine, or in other words, the supporting 15 wheels lie within or between lines coinciding with the edges of the mop. Furthermore, the rear wheels run in contact with the mop so that the latter keep the wheels clean and they will not leave streaks on the floor.

20 From the foregoing description taken in connection with the accompanying drawings, the advantages of the construction and method of operation will be readily understood by those skilled in the art to which the 25 invention appertains, and while we have described the principle of operation, together with the apparatus which we now consider to be the best embodiment thereof, we desire to have it understood that the apparatus 30 shown is merely illustrative and that such changes may be made when desired as fall within the scope of the appended claims.

Having thus described our invention, we 35 claim as new and desire to secure by Letters Patent:

1. In a machine of the class described, the 40 combination of a supporting structure, an endless mop, means for driving the same and removing the dirty water, a rotary scrubbing brush, a tank for cleaning fluid, means for supplying water from the tank to the floor at a point in front of the brush, means for sprinkling cleaning fluid on the mop as it moves out of contact with the 45 floor and toward the first-mentioned means, a cleaning brush operating on that portion of the mop on which the cleaning fluid is sprinkled, to remove dirt from the mop, a receptacle for receiving the removed dirt, 50 and a tank located within the mop and positioned under the first-mentioned means to receive the drippings therefrom, said mop being supported wholly out of the tank.

2. In a machine of the class described, the 55 combination of an endless mop, means for driving the same and removing the dirty water therefrom, a cleaning device arranged to operate upon that portion of the mop leaving the floor and passing to the said 60 means, a sprinkler for sprinkling a cleaning fluid on the mop at a point between the floor and the device, said cleaning device and sprinkler being located outside the mop, and a tank located within the mop for catching the dripping from the first-mentioned

means, said mop being supported with no part thereof in the tank.

3. In a machine of the class described, the combination of a supporting structure, a wringer thereon, an endless mop passing between the rolls on the wringer, and pressure 70 rolls on the structure for maintaining a portion of the mop stretched in a horizontal plane to bear on the floor, one of the rolls being adjustable to compensate for the 75 stretching and contraction of the mop, said frame having open slots forming bearings, the pressure rolls having journals resting in the bearings, whereby the rolls can automatically rise and fall independently of the 80 said supporting structure.

4. In a machine of the class described, the combination of a supporting structure, a wringer thereon, an endless mop passing between the rolls on the wringer, pressure rolls 85 on the structure for maintaining a portion of the mop stretched in a horizontal plane to bear on the floor, one of the rolls being adjustable to compensate for the stretching and contraction of the mop, and additional 90 rolls for guiding the mop, all of said rolls being removable from the structure, and the wringer being also removable with the mop hanging thereon.

5. In a machine of the class described, the 95 combination of a supporting structure, a wringer removably mounted thereon, an endless mop running between the rolls of the wringer, pressure rolls in the bottom of the said structure and under which the mop 100 runs to maintain a portion thereof in mopping engagement with the floor, and guide rolls on the structure and over which the mop runs, said rolls being removable to permit the mop to be removed with the wringer. 105

6. In a machine of the class described, the combination of a supporting structure, a wringer removably mounted thereon, an endless mop running between the rolls of the wringer, pressure rolls in the bottom of 110 the said structure and under which the mop runs to maintain a portion thereof in mopping engagement with the floor, and guide rolls on the structure and over which the mop runs, said rolls being removable to permit the mop to be removed with the wringer, 115 said wringer being made in separable sections for permitting of the removal or insertion of the mop.

7. In a machine of the class described, the 120 combination of a supporting structure, a wringer removably mounted thereon, an endless mop running between the rolls of the wringer, pressure rolls in the bottom of the said structure and under which the mop 125 runs to maintain a portion thereof in mopping engagement with the floor, guide rolls on the structure and over which the mop runs, said rolls being removable to permit the mop to be removed with the wringer, 130

and a tank disposed within the mop for receiving the drippings from the wringer and removable from the frame to permit the mop to be removed.

5. 8. In a machine of the class described, the combination of a supporting structure, an endless mop, pressure means for maintaining a portion of the mop in operative relation with the floor, a wringer removably mounted on the structure, and adjusting screws for moving the wringer toward and from the pressure means to vary the tension of the mop.

10. 9. In a machine of the class described, the combination of a supporting structure, wheels on which the structure moves, a tank on the structure for cleaning fluid, a scrubbing brush on the structure, means for supplying water from the tank to the floor at a point in front of the scrubbing brush, an endless mop behind the scrubbing brush,

means for supporting the mop, a wringer through which the mop passes, a tank for receiving the drippings from the wringer, a cleaning brush acting on the mop at a point 25 in advance of the wringer, a box for receiving the material discharged from the cleaning brush, and a mechanism for driving the wringer and cleaning brush and scrubbing brush.

15. 10. In a machine of the class described, the combination of a supporting frame, front and rear wheels for movably supporting the frame, and a mop mounted on the frame and having a portion in running contact 35 with the peripheries of the rear wheels.
